[57] ABSTRACT

In a game machine wherein the image of a road and the images of motor vehicles running on said road can be formed on a screen, there are provided at least one rotatable disc and at least one rotatable ring. The disc and the ring are so arranged that they form an annular space therebetween. Motor vehicle models carried by the disc and/or the ring are disposed in the annular space. A linkage connects a player operated accelerator pedal to an oscillating drive assembly to tilt the disc-ring assembly to produce an illusory effect of banking.

SIMULATED RACE DRIVING GAME

SUMMARY OF THE INVENTION

This invention relates to game machines which are adapted to form on a screen the images of a road and motor vehicles running on the road.

One type of the game machines described above which is known in the art comprises a plurality of transparent or semi-transparent discs carrying the image of a road and the images of motor vehicles respectively and mounted in parallel relationship for rotation relative to one another, a light source for projecting the images carried by the discs onto a screen, and drive means for rotating the respective discs. Moreover, a proposal has been made by the present inventor, although it has not yet been publicly known, to provide three-dimensional models of motor vehicles in place of the aforementioned images of motor vehicles in a space between two discs so as to form illusory three-dimensional images of motor vehicles on the screen.

In the game machines of the type referred to hereinabove, the light from the light source is transmitted through a plurality of transparent or semi-transparent discs, and transparent three-dimensional models in addition, depending on the type, so that the light is considerably reduced in amount when it reaches the screen. Besides, the light is refracted several times and consequently the images formed on the screen tend to be distorted. Part of the light is reflected when it is transmitted through the discs and forms ghost images on the screen in addition to regular images formed by the transmitted light. These are disadvantages of the conventional game machines.

This invention has as its object the provision of improvements in or relating to the game machines of the prior art so as to obviate the aforementioned disadvantages. According to the invention, there is provided a game machine comprising at least one rotatable disc, at least one rotatable ring mounted coaxially of such rotatable disc and disposed outwardly thereof, such disc and/or such ring each carrying a model or models of motor vehicles thereon, and a light source for projecting images of such models of motor vehicles on a screen, such disc and such ring defining therebetween an annular space which appears as a road on a screen, the models of motor vehicles being supported such that they are disposed in said annular space. By this arrangement, it is possible to form on the screen clear-cut images of the motor vehicle models which are free from distortion, because the light from the light source is transmitted only through the motor vehicle models before reaching the screen and is not transmitted through the disc or ring for carrying the motor vehicle models.

Additional features and advantages of the invention will become evident from the description set forth hereinafter when considered in conjunction with the accompanying drawings, in which:

FIG. 1 is a perspective view of the game machine according to this invention;

FIG. 2 is a schematic view showing the interior of the game machine;

FIG. 3 is a perspective view of the structure of the game machine in explanation of the principles of this invention;

FIG. 4 is a plan view of the rotating section of a first embodiment;

FIG. 5 is a sectional view taken along the line V—V of FIG. 4;

FIG. 6 is a sectional view taken along the line VI—VI of FIG. 4;

FIG. 7 is a sectional view taken along the line VII—VII of FIG. 4;

FIG. 8 is a sectional view taken along the line VIII—VIII of FIG. 2;

FIG. 9 is a sectional view taken along the line IX—IX of FIG. 8;

FIG. 10 is a sectional view taken along the line X—X of FIG. 8;

FIG. 11 is a plan view of the mechanism for shifting the light source support lever;

FIG. 12 is a side view of the mechanism of FIG. 11;

FIG. 13 is a view in explanation of another form of the motor vehicle model carrying mechanism;

FIG. 14 is a plan view of the rotating section of a second embodiment;

FIG. 15 is a sectional view taken along the line XV—XV of FIG. 14;

FIG. 16 is a sectional view taken along the line XVI—XVI of FIG. 14;

FIG. 18 is a view in explanation of the movable frame carrying the rotating section of the second embodiment;

FIG. 19 is a view in explanation of a third embodiment;

FIG. 20 and FIG. 21 are views in explanation of the motor vehicle model constructed according to this invention; and

FIG. 22 is a sectional view of another form of the motor vehicle model.

In FIG. 1, the game machine according to this invention is designated 1 which is provided with a front section modelled after the driving seat of a motor vehicle. It comprises a steering wheel 2, dashboard 3, wind shield 4 and accelerator 5. 6 designates a coin insertion slit.

In FIG. 2, there is shown drive means 7 housed in a casing of the game machine for oscillatory motion as subsequently to be described. Connected to the drive means 7 through a transmission are a rotary disc carrying a motor vehicle model, a rotary ring carrying a motor vehicle model, a rotary disc carrying background scenery, and a rotary ring carrying background scenery which can be rotated at different speeds. 8 is control means which can be operated through a connecting rope 9 by actuating the accelerator 5. The control means 8 is adapted to control, through conductors, a motor 10 for moving the drive means 7 in pivotal motion. 11 is a model for forming the image of the front portion of a motor vehicle simulatedly driven by the player on a screen 12.

In FIG. 3, there are rotatably mounted on outer rotary ring 13 carrying outer background scenery, an inner rotary ring 15 carrying a three-dimensional motor vehicle model 14 at its inner edge, an upper rotary disc 16 carrying three-dimensional motor vehicle models 14 at its outer edge, and a lower rotary disc 17 carrying inner background scenery. The inner rotary ring 15 and the upper rotary disc 16 are shown in the figures as carrying only one motor vehicle model respectively, but they can self-evidently carry two or more motor vehicle models. An annular space 18 is defined by the rotary

rings 13, 15 and rotary discs 16, 17 therebetween so that the three-dimensional motor vehicle models 14 may be disposed in the space 18. A lamp 19 is disposed above the rotary members 13, 15, 16 and 17. Of the light rays emitted by the lamp 19, light rays transmitted through the three-dimensional motor vehicle models 14 before reaching the screen 12 are only transmitted through the models 14 and relatively thin transparent support plates 20 each supporting the model in the angular space 18. This permits clear-cut images of the motor vehicle models to be formed on the screen.

In FIGS. 4 and 5, the upper rotary disc 16 carrying the three-dimensional motor vehicle model 14 is shown as being driven for rotation by a main drive motor 27 (See FIGS. 8 and 9) through a gear train 39-47 shown in FIG. 9, a shaft 21 and an intermediate member 22 secured to the shaft 21. The inner rotary ring 15 carrying the three-dimensional motor vehicle model 14 is driven for rotation by the main drive motor 27 through a gear train 48 to 56 shown in FIG. 9, a gear train 23 to 25, and a friction wheel 26. The outer rotary ring 13 carrying the outer background scenery is rotated by the motor 10 (See FIGS. 2, 8 and 10) through gears 28 and 29 and a friction wheel 30 (See FIG. 6). The lower rotary disc 17 carrying the inner background scenery is driven for rotation by the motor 10 through a belt wheel 31, a belt 32 and a belt wheel 33.

In FIG. 5, the inner rotary ring 15 is shown as being guided by a guide roll 34 while being held between the friction wheel 26 and the guide roll 34 which is supported for rotation about a fixed shaft disposed above the ring 15. Preferably, means 80 is provided for causing the rotary ring 15 to press against the friction wheel 26. The outer rotary ring 13 is provided with an upright wall 35 which serves as the background scenery in the distance. As shown, the upper rotary disc 16 is corrugated, so that the light rays are partly reflected by the corrugation and formed into scattered light. This is effective to prevent the formation of ghost images on the screen by reflected light rays.

In FIG. 6, the outer rotary ring 13 is shown as being guided, like the ring 15, by the guide roll 36 while being held between the friction wheel 30 and the guide roll 36 which is supported for rotation about a fixed shaft disposed above the ring 13. Means 81 is provided for causing the rotary ring 13 to press against the friction wheel 30.

The outer and inner rotary rings 13 and 15 are supported not only through the friction wheels 30 and 26 respectively as aforementioned but also in other supporting positions 37 and 38 (FIG. 4). Thus, the rings 13 and 15 are positively held in place by a three-point supporting system. The supporting positions 37 and 38 are similar in construction to each other, so that the construction of the position 38 will only be described.

In FIG. 7, two rollers 40 and 41 are shown as being loosely mounted, for rotation independently of each other, on a shaft 39 attached to members secured to a casing of the drive means 7. The roller 40 supports the outer rotary ring 13 and the roller 41 supports the inner rotary ring 15. Another roller 82 is provided for holding the outer rotary ring 13 between the rollers 40 and 82.

In FIGS. 8 and 9, the main drive motor 27 and motor 10 are mounted on the lower side of the casing of the drive means 7. Rotation of the main drive motor 27 is transmitted, on the one hand, through the gear train 38

5 to 47, to the shaft 21 to rotate the same, and rotation of the shaft 21 is transmitted through the intermediate member 22 to the upper rotary disc 16 to rotate the same. Rotation of the main drive motor 27 is transmitted, on the other hand, through the gear train 48 to 56 to an inner sleeve 57 rotatably mounted on the shaft 21 for rotating the sleeve 57, and rotation of the sleeve 57 is transmitted through the gear 23 firmly secured to the sleeve 57 to the inner rotary ring 15 for rotating the same, as has been explained with reference to FIG. 5.

10 The motor 10 rotates a shaft 60 through gears 58 and 59 as shown in FIG. 10. Rotation of the shaft 60 is transmitted through a gear 28 firmly secured to the shaft 60 to the outer rotary ring 13 for rotating the same, as has been explained with reference to FIG. 6. Rotation of the shaft 60 is also transmitted, through the belt wheel 31 and belt 32, to the belt wheel 33 for rotating the same, and rotation of the belt wheel 33 is transmitted, through an outer sleeve 61 firmly secured to the belt wheel 33, to the lower rotary disc 17 for rotating the same (See FIG. 9).

15 Firmly secured to the shaft 60 is a bevel gear 62 which is maintained in meshing engagement with a bevel gear 64 firmly secured to one end of a shaft 63 rotatably mounted on the casing of the drive means 7. Firmly secured to the other end of the shaft 63 is a shorter arm 65 of a double crank mechanism which is 20 pivotally connected, at an end of the arm 65 opposite to the end at which the arm 65 is secured to the shaft 63, to a longer arm 66 which, in turn, is pivotally connected to the machine frame through a shaft 67 which is connected to an end of the arm 66 opposite to the end at which the shorter arm 65 is pivotally connected. The casing of the drive means 7 is pivotally supported 25 by the machine frame through a support plate 68 and a pivotally supporting shaft 69.

30 A gear member 85 rotatably mounted on the sleeve 57 as shown in FIG. 9 is rotated by the gear 58 shown in FIG. 10 through gears 83 and 84. In this case, the gears 54 and 55 and gears 45 and 46 are mounted on the gear member 85 to serve as planetary gears for rotation with the gear member 85. The gears 54 and 55 and 45 and 46 revolve around the sun gears 53 and 56 and 44 and 47 respectively. By this arrangement, the 35 sleeve 57 and shaft 21 rotated through such planetary gears and hence the upper rotary disc 16 and inner rotary ring 15 carrying the motor vehicle models 14 are both caused to reverse their direction of rotation when the number of revolutions of the gear member 85 is increased or the pedal 5 is depressed with a greater force. This permits the player to simulate the outrunning of another motor vehicle by the motor vehicle he is driving on the screen.

40 In FIG. 11, a lever 70 supporting the light source 19 is shown as being pivotally supported at a pivot 71. A tension spring 72 is connected at one end thereof to a portion of the lever 70, and a connecting rod 73 is connected at one end thereof to a portion of the lever 70 disposed to the portion thereof at which the tension spring 72 is connected. The tension spring 72 is connected at the other end thereof to a frame attached to the casing of the drive means. The connecting rod 73 is connected at the other end thereof to one end of a two-arm lever 75 pivotally connected to the frame through a pivot 74 (See FIG. 12). Connected to the other end of the two-arm lever 75 is one end of a wire 76 which is connected at the other end thereof to a

rack 77 shown in FIG. 2. In FIG. 2, the rack 77 is shown as being maintained in meshing engagement with a pinion 79 mounted at an end of a shaft 78 supporting at the other end thereof the steering wheel 2. As the steering wheel 2 is operated, the rack 77 is shifted perpendicular to the plane of FIG. 2. A bar 80 shown in FIG. 11 is for supporting the model 11 of the forward portion of a motor vehicle shown in FIG. 2.

When the steering wheel 2 shown in FIG. 2 is operated to shift the rack 77 through the pinion 79 in a direction in which the wire 76 is tensioned, for example, the two-arm lever 75 shown in FIG. 12 is moved in pivotal motion in an counterclockwise direction about the pivot 74, so that the support lever 70 is moved, through the connecting rod 73, in pivotal motion in a clockwise direction in FIG. 11 against the biasing force of the tension spring 72. Thus, the lamp 19 is shifted in FIG. 11 with respect to each rotary disc and each rotary ring, and hence with respect to the annular space 18 representing a road on the screen. It will be readily understood that, if the steering wheel 2 is operated in opposite direction for loosening the wire 76, then the lamp 19 is shifted in opposite direction.

When a predetermined coin is inserted into the coin slit 6, a main switch of this machine is turned on so as to supply power to the main drive motor 27 and lamp 19. Accordingly, the inner rotary ring 15 and upper rotary disc 16 carrying the respective three-dimensional motor vehicle models 14 are rotated as aforementioned so as to form the images of running motor vehicles on the screen. Since the rotary ring 15 and rotary disc 16 rotate at different rates of revolution, the motor vehicle running along the inner side of the road and the motor vehicle running along the outer side of the road on the screen appear to be running at different speeds.

When the pedal 5 shown in FIG. 1 is depressed, the motor 10 is actuated, so that the outer rotary ring 13 carrying the outer background scenery and the lower rotary disc 17 carrying the inner background scenery are rotated to give an illusory effect of the scenery outside and inside the road moving together. Thus, the image of the model 11 which simulates the motor vehicle driven by the player runs on the screen as if the motor vehicle were actually driven by the player.

Actuation of the motor 10 also results in a unit consisting of the rotary discs, rotary rings and drive means being moved in oscillatory motion about the pivotally supporting shaft 69 by the action of the double crank mechanism 65, 66. This produces an illusory sensation of the road and horizon being inclined and makes the player feel as if the motor vehicle he or she is driving were listing while running along the curved road, thereby realistically representing the banking of the motor vehicle on the curved road.

In this connection, it should be noted that the rate of rotation of the motor 10 can be controlled through the control means 8 by adjusting the force with which the accelerator 5 is depressed, causing the rotary disc carrying the background scenery and the rotary ring carrying the background scenery to rotate at different speeds. This causes a change to occur in the rate of movement of the image of scenery on the screen and hence a change to occur in the speed of the motor vehicle driven by the player, and at the same time results in a change in the degree of banking of the motor vehicle. Besides, the motor vehicle driven by the player

passes another motor vehicle ahead at this time, as aforementioned.

As explained with reference to FIGS. 11 and 12, the lamp 19 is shifted when the steering wheel 2 is operated by the player. This causes the position of the rod on the screen to move to left and right and produces an illusory sensation of the motor vehicle driven by the player drawing nearer to one side of the road.

In place of supporting each of the three-dimensional 10 motor vehicle models 14 on the transparent plate 20 as shown in FIGS. 3, 4 and 7, a positive picture of a motor vehicle may be attached to the transparent plate 20 or a picture of motor vehicle may be drawn directly on the transparent plate 20.

15 Instead of supporting each of the three-dimensional motor vehicle models on the transparent plate 20, the model 14 may be mounted directly on the outer edge of the upper rotary disc 16 and/or the inner edge or a member projecting inwardly from the inner edge of the 20 inner rotary ring 15, as is shown in FIG. 13. If this is the case, the light will be only transmitted through the three-dimensional motor vehicle models before reaching the screen, thereby ensuring that the images on the screen are more clearly defined than would be the case 25 if the model were mounted otherwise.

In the present invention, it is not essential to attach the model of the motor vehicle to both the inner rotary ring 15 and upper rotary disc 16. Instead, either the inner rotary ring 15 or the upper rotary disc 16 may 30 carry the models. If this is the case, the images of motor vehicles in the screen will run at the same speed.

In the embodiment of the invention described hereinabove, power is transmitted from the drive motor to each rotating section through a gear train. This arrangement involves a large number of gears used and hence a high cost of production. Another embodiment 35 which is simpler in construction and lower in cost will presently be explained.

40 In FIG. 14, the upper rotary disc 16 carrying the three-dimensional motor vehicle model 14 is shown as being driven for rotation by a drive motor M1 (See FIG. 15) through a shaft 121 and an intermediate member 122 secured to the shaft 121, and the inner rotary ring 15 carrying the three-dimensional motor vehicle model 14 is shown as being driven for rotation by a drive motor M2 (See FIG. 16) through a shaft 86 and a friction wheel 126 secured to the shaft 86. The outer rotary ring 13 carrying outer background scenery is driven for rotation by a drive motor M3 (See FIG. 15) 45 through a shaft 87 and a friction wheel 130 secured to the shaft 87. The lower rotary disc 17 carrying the inner background scenery is driven for rotation by a belt 132 trained about a belt wheel 133 firmly secured to a sleeve 88 loosely mounted on the shaft 121 supporting the rotary disc 17 and a belt receiving groove 50 55 89 formed in the boss of the friction wheel 130 (See FIG. 15).

As shown in FIGS. 17 and 18, a movable frame 90 is 60 pivotally connected to a machine frame 92 through a shaft 91. As shown, a support frame 93 is mounted on a support plate 90a firmly secured to the movable frame 90. A shaft 94 is rotatably journaled by the support frame 93. Firmly secured to the shaft 94 is a worm gear 95 which is maintained in meshing engagement with a worm 96 firmly secured to the shaft 87 of the drive motor M3 (FIG. 15). An arm 97 is firmly secured 65 to one end thereof to a free end of the shaft 94. Firmly

secured to the other end of the arm 97 is a shaft 98 which supports at one end thereof a wheel 100 adapted to move in rolling motion along a rail 99 provided on the machine frame. When the drive motor M3 is rotated, the shaft 94 is rotated through the worm 96 and worm gear 95, and the movable frame 90 moves in oscillatory motion about the shaft 91 by virtue of the action of wheel 100 and arm 97. 101 is a wheel which is adapted to move in rolling motion while being maintained in contact with the machine frame when the movable frame 90 moves in oscillatory motion about the shaft 91.

If a predetermined coin is inserted in the coin slot of the embodiment shown in FIGS. 14 to 18, a main switch of the machine will be turned on to supply power to the motors M1 and M2 and lamp 19 to rotate the inner rotary ring 15 and the upper rotary disc 16 carrying the respective three-dimensional motor vehicle models as is the case with the first embodiment. When the pedal 5 shown in FIG. 1 is depressed, the motor M3 is actuated through the control means 8 (FIG. 2) to rotate the lower rotary disc 17 carrying the inner background scenery and the outer rotary ring 13 carrying the outer background scenery. Rotation of the motor M3 is transmitted, through the worm 96 firmly secured to the motor shaft, worm gear 95, shaft 94 to which the worm gear is firmly secured, arm 97, shaft 98 and wheel 100 mounted on the shaft 98 for movement along the guide rail 99, to the movable frame 90 so as to cause the same to move in oscillatory motion about the shaft 91. This gives an illusory effect of banking of the motor vehicles to the images of motor vehicle models on the screen as is described with reference to the first embodiment.

In this case, it is possible to control the rates of rotation of the motors M1, M2 and M3 by varying the force with which the pedal 5 is depressed. By gradually increasing the force with which the pedal is depressed, the speeds of the motors M1 and M2 are gradually reduced till finally the direction of rotation is reversed, thereby giving an illusory effect of the motor vehicle driven by the player passing other motor vehicles ahead to the images of motor vehicle models on the screen. An increase in the force with which the pedal 5 is depressed further causes an increase in the speed of motor M3, thereby increasing the rates of revolution of the rotary disc 17 and rotary ring 13 carrying the inner background scenery and outer background scenery respectively. This gives an illusory effect of an increase in the speed of the motor vehicle driven by the player and an increase in the degree of banking thereof to the image of motor vehicle model running on the screen.

The shaft 94 for giving rise to a banking phenomenon may be driven by another motor instead of by the motor M3. The shaft 94 is shown as being connected to a fourth motor M4 in FIG. 19. This arrangement permits to use a motor of relatively small capacity as the motor M3 and to do without the worm 96 and worm gear 95 shown in FIG. 17.

From the foregoing description, it will be appreciated that almost all the rotating sections are each provided with a motor for directly driving the rotating sections in this embodiment. This permits to greatly reduce the number of gears which are used in the first embodiment and to use motors which are relatively low in cost, thereby permitting to greatly reduce the overall cost of the game machine. Besides, the paucity of the number

of gears used renders the machine free from trouble and highly durable. Another advantage is that, since rotation of each drive motor can readily be adjusted by controlling voltage by means of a variable resistor, the speed of motor vehicle model running on the screen can readily be varied.

According to this invention, there is provided a three-dimensional motor vehicle model which permits to reduce the number of solid parts of the model 10 through which light is transmitted, so as to form a clear-cut image of the model on the screen. In FIGS. 20 and 21, a three-dimensional motor vehicle model according to this invention is generally designated 114. The model 114 comprises a three-dimensional hollow body 102 made of a transparent or semi-transparent plate of synthetic resin and having an open bottom. The body 102 is secured to and supported by a frame 103 of the chassis shape made of a relatively thin wire or a stamped material. The frame 103 of the chassis shape 15 is formed with axle-like projections 104 each of which mounts a hollow wheel 105 made of a transparent or semi-transparent plate of synthetic resin. Since the model 114 is open at the bottom, light is only transmitted once through the model. This greatly reduces the 20 damping factor of light.

The three-dimensional motor vehicle model illustrated in FIG. 22 comprises the body 102 and wheels 105 formed integrally of a transparent or semi-transparent plate of synthetic resin, so that the model 30 does without the frame 103 of the chassis shape made of a wire of the model shown in FIGS. 20 and 21. The body 102 and wheels 105 may be made separately and the axles of wheels 105 may be attached, adhesively or otherwise, to side walls of the body 102.

From the foregoing description, it will be appreciated that the light transmitted through the graphically represented motor vehicles or motor vehicle models before reaching the screen is not made to pass through other members such as discs or the like which carry the graphic images or models, so that it is possible to form clear-cut images on the screen. Combined with the transverse movement of the road effected by operating the handle and the banking effect produced by controlled operation of the accelerator, this makes the player feel as if he or she were actually driving a motor vehicle and increases the amusement value of the game machine.

Certain terminology will be defined. The "motor vehicle model" referred to in the claims is intended to include a three-dimensional motor vehicle model and a graphically represented motor vehicle as has been described. The "motor vehicle" may also include a three-dimensional or graphically represented motorcycle model. In this case a steering handlebar is disposed in the front section shown in FIG. 1 instead of the steering wheel 2, the steering handlebar having a or twist grips for changing the speed of motorcycle and the accelerator 5 shown in FIG. 1 being able to be omitted.

What we claim is:

60 1. A game machine wherein the image of a road and the images of motor vehicles running on said road can be formed on a screen, such game machine comprising a first rotatable disc carrying a motor vehicle model, a second disc carrying background scenery and mounted coaxially with said first rotatable disc to be disposed downwardly thereof for rotation independently thereof, a first rotatable ring carrying a motor vehicle

model and mounted coaxially with said first and second disc to be disposed outwardly thereof, a second ring carrying background scenery and mounted coaxially with said first ring to be disposed adjacent thereto for rotation independently thereof, and a light source for projecting the motor vehicle models onto a screen, said discs and said rings defining therebetween an annular space which appears as a road on the screen, said motor vehicle models being carried such that they are disposed in said annular space.

2. A game machine as defined in claim 1 wherein said first disc disposed upwardly of said second disc carrying background scenery is made of a transparent corrugated sheet material.

3. A game machine as defined in claim 1 further comprising a motor for operating said first rotatable disc carrying a motor vehicle model which is actuated upon turning on of a main switch of the machine, a motor for operating said first rotatable ring carrying a motor vehicle model which is actuated upon turning on of the main switch of the machine, and a motor for operating said second rotatable disc carrying background scenery and said second rotatable ring carrying background scenery which is actuated upon depressing of the accelerator by the operator.

4. A game machine as defined in claim 1 further comprising a motor for operating said first rotatable disc carrying a motor vehicle model which is actuated upon turning on of a main switch of the machine, a motor for operating said first rotatable ring carrying a motor vehicle model which is actuated upon turning on of the main switch of the machine, a motor for operating said second rotatable disc carrying background scenery and said second rotatable ring carrying background scenery which is actuated upon depressing of the accelerator by the operator, and a motor for operating in oscillatory motion the discs, rings and means for operating said discs and said rings as a unit which is actuated upon depressing of the accelerator by the operator.

5. A game machine as defined in claim 1 wherein said motor vehicle model is a painted three-dimensional model made of a transparent or semi-transparent material and constructed to have an open bottom.

6. A game machine wherein the image of a road and the images of motor vehicles running on the road can be formed on a screen, such game machine comprising at least one rotatable disc, at least one rotatable ring

mounted coaxially with said rotatable disc and spaced radially outwardly from the circumferential periphery of said disc, said disc and said ring defining therebetween an open annular space in the plane of said disc which appears on the screen as a road, at least one first motor vehicle model secured to and extending radially outwardly from the circumferential periphery of said disc and located in the open annular space in the plane of said disc, said first model having a length which is a minor portion of the length of the annular space and being arranged so that it appears to be travelling in the direction of the annular space, said first model arranged in the annular space with its forward side, rearward side and side located laterally outwardly from said disc spaced from any adjacent surface, at least one second motor vehicle model secured to and extending radially inwardly from the inner circumferential periphery of said ring and being located within the open annular space radially outwardly from the circumferential periphery of said disc and in the plane of said disc, said second motor vehicle model having a length which is a minor portion of the length of the annular space and being arranged so that it appears to be travelling in the direction of the annular space with its forward side, rearward side and side located laterally inwardly from said ring spaced from any adjacent surfaces, and a light source positioned for transmitting light rays through the open annular space so that the only structures located in the annular space are said first and second motor vehicle models for projecting the image of said motor vehicle models on the screen without having the light rays which project the images of said first and second motor vehicle models passing through any other structure.

7. A game machine as defined in claim 6, including means for operating said disc and said ring as a unit, means for moving in oscillatory motion said disc, ring and means for operating said disc and said ring as a unit, said means for moving in oscillatory motion being actuated upon depressing of an accelerator for producing an illusory effect of banking of the motor vehicle to the image of the motor vehicle formed on the screen.

8. A game machine as defined in claim 6 further comprising means for moving said light source relative to the disc and ring, said means being actuated upon operating of a steering wheel by the player.
